Attorney

UNITED STATES PATENT OFFICE.

ARTHUR J. PRATT, OF CAMBRIDGE, MASSACHUSETTS, ASSIGNOR TO AMERICAN OPTICAL COMPANY, OF SOUTHERIDGE, MASSACHUSETTS, A VOLUNTARY ASSOCIATION OF MASSACHUSETTS.

CASE.

Application filed July 5, 1927. Serial No. 203,351.

This invention relates to improvements in receptacles and has particular reference to a receptacle for an eyeglass or spectacle frame.

The principal object of this invention is to provide simple, efficient, inexpensive and ornamental means for providing a dust-proof receptacle and to provide terminal abutments for the lining of the cover that will hold it in place and prevent it being displaced, fraying out, etc.

Other objects and advantages of the invention will become apparent from the following description taken in connection with the accompanying drawings, and it will be apparent that many changes in the details of construction and arrangement of parts may be made without departing from the spirit of the invention as expressed in the accompanying claims. I, therefore, do not wish to be limited to the exact details of construction shown and described, the preferred forms only having been shown by way of illustration.

Referring to the drawings:

Fig. 1 is a front view of a receptacle embodying the invention.

Fig. 2 is an end view of Fig. 1.

Fig. 3 is a cross section on line 3—3 of Fig. 1.

Fig. 4 is a cross section on line 4—4 of Fig. 2.

Prior to my invention the tops or lids of receptacles of this character were constructed so as to overlie flatly the base or bottom. This construction was not dust-proof owing to the fact that somewhere throughout its length the lid would spring away from the bottom, this difficulty being experienced even in new cases as they came from the factory and developing rapidly in use. Another defect of such cases was that the lining in the top having no terminal abutment became separated from the top and frayed out, producing an ungainly appearance and practically destroying the value of the receptacle.

Referring to the drawings wherein similar characters of reference denote corresponding

parts throughout, the receptacle comprises a top 1 hinged to a base 2 by a hinge 3. The base 2 has an overhanging lip 4 over which the cover 1 laps. Within both the bottom and the cover is a lining 5 of velvet or other soft finishing material which is usually secured in place by cement or other adhesive mediums. The cover 1 and bottom 2 of the receptacle may be of metal, such as polished aluminum or other metal, or it may be of a non-polished metal base covered with cloth, leather or other material.

It will be noted that in the cover 1 I have provided a knuckle or bend 6 at the outermost edge of the front of the cover where it overlies the lip 4 of the base 2. The object of this knuckle or bend is two-fold. In the first place it provides a square shoulder or retaining abutment for the end of the lining 5, guarding it against being pulled loose or fraying out. In the second place it provides a sharp edge engaging portion 7 for engaging the lip portion 4. The knuckle being in the form of a bent portion it is not as easily deflected or bent as an unknuckled member. This knuckling at 6 not only insures a tight engaging dust-proof contact at 7, but also insures that the contact will be maintained in service as it will not be bent away as in the prior art cases forming openings through which the dirt and dust may seep.

From the foregoing it will be seen that I have provided simple, efficient and inexpensive means for carrying out all of the objects of the invention, and that I have thus secured a dust-proof receptacle which will maintain its dust-proof contact in service and at the same time provide a guard and protection for the edge and end of the lining.

Having described my invention, I claim:

1. In a device of the character described, a base having a lip overlying a portion thereof, a cover having an inturned edge portion overlying the lip whereby the edge of the inturned portion engages the lip to form a dust proof contact therewith, and a lining on the inside of the cover having one

edge abutting and protected by the inturned edge portion.

2. In a device of the character described, a base having a lip overlying a portion thereof and a cover having a bent inturned edge portion overlying the lip throughout the length of the lip whereby the edge of the

inturned portion engages the lip to form a dust proof contact therewith, said inturned edge portion forming a stiffening member along the line of contact of the inturned edge. 10

ARTHUR J. PRATT.
